UNITED STATES PATENT OFFICE.

GUY DU PRIEST, OF AUSTIN, TEXAS, ASSIGNOR TO JOSEPHINE NOLEN, OF AUSTIN, TEXAS.

DESIGN FOR AN ADVERTISING SIGN.

Application filed January 11, 1928. Serial No. 24,816. Term of patent 14 years.

To all whom it may concern:

Be it known that I, GUY DU PRIEST, a citizen of the United States of America, residing at Austin, in the county of Travis and State of Texas, have invented a new, original, and ornamental Design for an Advertising Sign, of which the following is a specification, reference being had to the accompanying drawings, forming a part thereof.

I claim:—

The ornamental design for an advertising sign as shown.

GUY DU PRIEST.
